UNITED STATES PATENT OFFICE

WALTER DÄLLENBACH, OF ZURICH, SWITZERLAND

LEADING-IN DEVICE FOR METALLIC VACUUM-DISCHARGE CONTAINERS

Application filed March 18, 1929, Serial No. 347,965, and in Germany April 2, 1928.

This invention relates to leading in devices for metallic vacuum-discharge containers of the kind wherein the metal parts that are situated in vacua, and influence the electric field in the neighbourhood of the insulator sealing the vacuum, are exposed to high and changing temperatures. As these metal parts must be securely held in position on account of differences of electric potential between them, screws and riveting have been found unreliable in practice. One example of leading-in device of the kind referred to is described in the applicant's copending U. S. application, Ser. No. 170,505 filed

15 March 18, 1929.

An important object of the present invention is to provide an improved construction of leading-in device of the kind described wherein the said metal parts are held in their 20 position in an improved manner.

According to the invention there is provided a leading-in device of the kind described (for example according to my above mentioned application, Ser. No. 170,505) for 25 a metallic vacuum-discharge container, wherein the metallic parts that are situated in vacua, and influence the electric field in the neighbourhood of the insulator sealing the vacuum, are held fast in their position at 30 least in part by soldering, brazing, or welding, for example spot-welding, or like securing means.

In the case of a vacuum-sealing insulator this mode of attachment is of particular importance when the insulator consists of a glass tube fused to two metal tubes. When the two metal tubes are machined exactly they may nevertheless change their shape slightly or warp somewhat during the fusing operation. 40 Further, it is not possible for a glass-blower to put two metal tubes connected by the glass tube in such an exactly coaxial position relatively to one another as can be done with machined metal parts fitting one on another. 45 It is much easier to avoid such irregularities

when the metal parts influencing the field are erected by means of welding or soldering at places instead of using rivets, screws or the like.

The metal parts influencing the field will, 50 at least in part, be fixed rigidly relatively to the two metal tubes adjoining the vacuum-sealing insulator. As these two tubes, in general, are not positioned sufficiently exactly coaxially relatively to one another, according to another feature of the invention the metal parts are at least in part arranged coaxial to an axis that is central 55 relatively to the two metal tubes.

The device may be constructed as follows:—

The parts to be assembled together with the glass-metal assembly, such as the electrode-neck or conductor, the protective cylinders which, according to the specification 65 No. 170,505 almost cover over the faces of the insulator towards the vacuum, as well as other parts, protective tubes, caps and the like, which exert an influence on the field-distribution in the neighbourhood of the insulator, are clamped by a suitable mount coaxially to a central axis of the glass-metal assembly and then held in this position by welding or soldering. The line connecting the 70 centers of two spheres which can be described in the two metal tubes near their fused edges may be taken, for example, as the middle longitudinal axis of the glass-metal assembly. The welding or soldering can be done electrically with the arc or as spot-welding or with a flame.

One embodiment of the invention is diagrammatically illustrated by way of example in the accompanying drawing, wherein:—

Figure 1 is a vertical section showing one form of leading-in device according to the invention, and

Figure 2 is a horizontal section taken on the line II—II in Figure 1.

Like reference characters designate like parts in both views.

Referring to the drawing, W denotes the wall of the container or evacuated vessel, S 5 the conductor, and G is the glass insulator fused with the metal tubes R₁ and R₂ and together constituting a glass-metal assembly referred to above. B₁ and B₂ are metal cylinders which establish the desired potential 10 distribution at the inner surface of the glass insulator G. The cylinders B₁ and B₂ are centered relatively to the tubes R₁ and R₂ by annular bosses U of triangular section. They are held rigidly in their position by lugs D 15 which are welded both to the tubes R₁, R₂ and to the cylinders B₁, B₂. Even if the tubes R₁, R₂ are not coaxial it is possible to weld the connecting or spacing members D in position in such a manner that the cylinders B₁, 20 B₂ are arranged coaxial with the line joining the centers of the bosses U.

It is to be understood that various modifications may be made in the details of construction described above without departing 25 from the scope of the invention as defined in the claims. In this connection it will be quite obvious that the cylinders B₁, B₂ may be rigidly and accurately held in position either by welding or soldering, and in the following 30 claims it will be understood that the expression "fused electrically conductive connection" as referring to the manner in which the cylinders B₁, B₂ are connected with the parts associated therewith is intended to cover 35 either welding or soldering.

I claim:—

1. In a vacuum discharge vessel of metal containing a rarefied fluid, the combination 40 of a leading-in conductor, an insulator sealing said leading-in conductor in said vessel, and conducting parts covering that portion of the surface of said insulator adjoining the vacuum, said conducting parts being slightly spaced from the insulator, one conducting 45 part being electrically connected with said leading-in conductor, the other conducting part being electrically connected with said vessel, these conducting parts being separated by a narrow gap in which the drop in potential 50 between said vessel and said leading-in conductor is concentrated, said gap being located from the points of contact of said insulator and the conducting parts in the vacuum at a distance forming a multiple of its width, and fused electrically conductive connections holding said conducting parts in 55 position.

2. In a vacuum discharge vessel of metal 60 containing a rarefied fluid, the combination of a leading-in conductor, two metallic tubes connected respectively with the leading-in conductor and the vessel, a glass tube fused coaxially with the metal tubes, conducting 65 parts covering that portion of the surface of

the glass tube adjoining the vacuum, said conducting parts being slightly spaced from said glass tube, a fused electrically conductive connection between one conducting part and one of the metal tubes and between the other conducting part and the other metal tube, said conducting parts being separated by a narrow gap in which the drop in potential 70 between said vessel and said electrode is concentrated, said gap being located from points of contacts of said insulator and the conducting parts in the vacuum at a distance 75 forming a multiple of its width.
